METHOD AND APPARATUS FOR FORMING
CONCRETE FOUNDATION COLUMNS

William J. Newman, Chicago, Ill.

Application March 12, 1932, Serial No. 598,397
Renewed May 7, 1938

6 Claims. (Cl. 61—57)

This application relates to foundations or underground constructions wherein holes or wells are drilled or excavated while keeping the same filled with water or muck and are then filled 5 with concrete or the like to form columns, foundation, or wall members. The invention is particularly applicable to such methods in which relatively large wells, of five feet or more in diameter, and of considerable depth, are drilled 10 down to a bed of solid rock or other similar structure adapted to support the column.

The objects of this invention are to provide an improved foundation structure and method of constructing the same; to provide an improved 15 method of filling wells with concrete; to provide means whereby a portion of a well filled with water or muck may be closed off to permit access to the bottom for inspection or cleaning; to provide means for making a closure between an 20 open pipe and the bottom of a well filled with water whereby the water may be pumped out of the pipe without drawing the same from the space between the pipe and the walls of the well; to provide a novel cutting device adapted to cut 25 a slot for receiving the same in the bottom of a well, which device also serves for making a joint or closure in the pipe; and in general to provide such new devices and methods as will be described more fully hereinafter.

30 In the accompanying drawings illustrating this invention;

Figure 1 is a vertical sectional view of a well showing my improved cutting apparatus in operative position;

35 Figure 2 is a view similar to Figure 1 showing the circular cutter embedded in the rock or bottom of the well and also showing the inspection and filling pipe, reinforcing rods, and other parts in position preparatory for placing the concrete;

40 Figure 3 is a similar view illustrating the placing of the concrete;

Figure 4 is a cross sectional view taken on the line 4—4 of Figure 1; and

45 Figure 5 is a detail of one of the sockets or bayonet joint driving members for the cutter.

The well 6 is drilled by means of any suitable drilling apparatus and is preferably kept filled 50 with water or muck 7 during the entire drilling operation, a large proportion of the excavated material preferably being left in the water, thus increasing the specific gravity and keeping sufficient pressure on the side walls 8 to prevent the walls from caving in. These wells are frequently of five feet or more in diameter and upwards of 55 one hundred feet in depth and are preferably

drilled down to a layer 9 of bed rock or other suitable formation upon which the foundation may rest.

After the well is drilled, the drilling apparatus is removed and a spider or driving head 10 attached to the lower end of the drill pipe or rod 11. In the construction shown, the drill pipe is provided with a flange 12 which engages with a flange 13 on the spider and these parts are connected by bolts 14. The adjacent faces of the 10 flanges may be provided with interlocking lugs or teeth 15 to prevent undue strain on the bolts. The spider has a plurality of radially arranged lugs or projections 16 which are adapted to engage with slots or recesses 17 in driving brackets 15 18 on the inner periphery of a cylindrical cutter 19. The slots 17 are preferably of bayonet joint form, as shown in Figure 5, so that the cutter may be supported on the spider and lowered into position and turned by the spider when it is 20 driven in one direction. The spider may then be disconnected from the cutter by rotating it a short distance in the opposite direction so that the projections 16 are free to move upwardly out of the bayonet joint slots. 25

The circular cutter 19 may be of any suitable type or form for cutting a kerf in the bed 9 so that a portion thereof will be embedded and sealed in such kerf or slot. The form shown comprises a tubular section preferably made of 30 sheet steel and having cutting teeth 20 or a serrated lower edge as shown.

When the cutter has been lowered to the bottom of the well it is rotated by the spider 10 and drill pipe 11 in the proper direction for cutting 35 and this is continued until the cutter has made a circular kerf or groove for a substantial distance into the bed rock 9 and so that water is not apt to pass down around the lower end thereof. In other words, the cutter is embedded in 40 the rock and the rock makes a tight closure for the lower end thereof. After the cutter has thus been implanted in the rock, the spider is turned in the reverse direction until the drive portions 16 are free to be raised out of the slots and the 45 string of drill pipe with the spider are then removed from the well.

A pipe 21 is then lowered into the well and extends from above the top of the same down to the bottom. The lower end of this pipe rests 50 on the upper end of the cylindrical member 19 and any suitable means may be provided for making a tight joint between these members. In the arrangement shown, the pipe 21 is provided with a conical or outwardly tapered portion 55

22 at the bottom and a gasket 23 is secured thereto, this gasket being formed of any suitable packing material. The gasket engages with the upper tapered end 24 of the cutter 19 as shown in Figure 2, thus making a tight joint between the parts. The pipe 21 is lowered into the well while the well is still filled with water or muck and will usually be of comparatively great weight so that it tends to press the cylindrical member 19 10 downwardly and to make a tight closure between the pipe and the bottom of the well. When this pipe has been thus placed in position the water is pumped out of the pipe and the upwardly projecting portion of the cylindrical member 19 15 but the water or muck between the pipe and the sides of the well remains in position. The pipe 21 is preferably of sufficient diameter so that a man can pass down through the same and examine the bottom and determine whether it is of 20 a satisfactory character before the concrete is poured. Furthermore, he may clean off the bottom surface within the cutter 19 so that a satisfactory bond may be made between the bed rock and the concrete.

25 Having the filling pipe or tremie 21 in position and the bottom properly prepared, the work is in condition for the filling operation. If the concrete is to be reinforced, the reinforcing rods 25 are placed in position within the pipe 21 and 30 extend from the top of the well to the bed rock 9.

In order to prevent the mixing of the muck or mud with the concrete I provide a pipe or discharge head 26 which passes around or engages with the flange 22 and which has downwardly facing holes 27 for the discharge of air or fluid under pressure. The air is supplied to this discharge member by a pipe 28 which leads to the top of the well and which is provided with a valve 29. The air or steam 40 which is preferably used may be supplied from any suitable source. I have found that in some cases there is a tendency of the mud or excavated material to settle against the sides of the well and adhere thereto so that it will prevent the 45 concrete from extending across or filling the entire area of a well. The air or steam which is forced downwardly and outwardly through the discharge holes tends to thoroughly agitate the mixture and loosen any material which may tend 50 to adhere to the sides of the well so that the side walls will be substantially clean when the concrete is poured into the well.

The concrete is poured into the pipe 21 and passes down to the bottom and fills the cutter 55 member 19 which is to remain in position in the bottom of the well. The pipe 21 preferably extends above the top of the well and is at all times kept filled with concrete in order to prevent water from the outside of the pipe passing 60 down and into the lower end thereof. When the pipe 21 has been filled, air is forced down through the pipe 28 and is carried around the periphery of the flange 22 and discharged downwardly so as to thoroughly stir up the muck and 65 tend to hold the solid particles in suspension preparatory for the discharge of the concrete. The pipe 21 is then gradually raised so that the concrete pours out at the bottom and completely 70 fills the well as shown in Figure 3. The concrete is added to the supply in the pipe 21 and the air is continued to be discharged around the lower end as the work progresses so that the walls of the well are kept clean and a solid mass of concrete is made which will be thoroughly 75 bonded with the sides of the well. By this means

a substantial foundation will be provided and the column in some instances will be substantially supported, for all practical purposes, by the side walls even if the bed or bottom was not entirely satisfactory. It will of course be noted that sections of the pipe 28 will be removed as the work progresses or a hose might be used for this purpose, which could be gradually drawn out of the well. 5

While I have shown one embodiment of the 10 apparatus adapted for use for carrying out my process, it will be noted that other forms may be utilized and therefore I do not wish to be limited to the particular construction or the steps of the method herein described except as 15 set forth in the following claims in which I claim:

1. The herein described method which consists in placing a rotary, cylindrical cutter in the bottom of a hole filled with water and rotating the 20 same to cause the lower end to be embedded in the bottom and make a tight closure therewith, then removing the rotating mechanism and leaving the cutter in position, then lowering a pipe of sufficient diameter to permit a man to pass 25 through the same, into the hole, said pipe having a flange at its lower end and a packing member adapted to engage with the upper end of the cutter to make a tight joint therewith, then pumping the water out of the pipe and cutter 30 while leaving it in the surrounding portion of the hole, then inspecting the bottom within the cutter and cleaning the same, then filling the pipe with concrete and utilizing the same as a tremie for filling the hole, and simultaneously agitating the water around the lower end of the pipe 35 as the filling proceeds.

2. The herein described process which consists in detachably supporting a cylindrical cutter on a well drilling pipe, lowering the cutter 40 to the bottom of a well filled with water or muck, and rotating the same until the lower edge makes a tight closure with the bottom of the well, then removing the drill pipe and leaving the cutter in position, then placing a pipe in the well with its 45 lower end making a tight joint with the upper end of the drill member, then pumping the contents out of the pipe and drill member, then making a survey of the bottom within the drill member, then placing reinforcing rods within 50 the pipe with their lower portions resting on the bottom of the well, then filling the pipe with concrete and gradually raising the same to deposit concrete in the well, and simultaneously agitating the contents of the well adjacent to the 55 bottom of the pipe by means of fluid under pressure.

3. The combination with a cylindrical member adapted to make a sufficiently tight closure with the material forming the bottom of a well to prevent water or other contents of the well from flowing into said member at the lower end thereof, of a tremie having a flange at the lower end thereof, and a gasket arranged between the tremie and the cylindrical member to make a 60 water tight joint, and means around the outer surface of the tremie for discharging fluid under pressure.

4. The combination with a cylindrical cutter of the character set forth, having a tapered upper 70 end, of a pipe having a tapered flange and adapted to rest on said cutter, a gasket interposed between the flange and the tapered end of the cutter, a pipe around said flange having downwardly facing holes and means for supply- 75

ing fluid under pressure to said last named pipe.

5. The method of constructing under-ground foundations which consists in sinking a well and keeping the same filled with water and more or less of the excavated material until a suitable stratum is reached, then inserting a cylindrical member in the well and rotating the same on said stratum until it makes a tight joint therewith, then inserting a large pipe which is open at both ends in the well and making a watertight joint between the pipe and said cylindrical member, then withdrawing the contents of the pipe in the cylindrical member while leaving the surrounding space in the well filled, then utilizing the pipe as a tremie for depositing concrete in the well and simultaneously agitating the water and material contained therein around the

lower end of the pipe by means of air as the pipe is raised.

6. An apparatus of the character set forth, including a tubular member having open ends adapted to be placed in a well filled with water and excavated material said tubular member being of less diameter than the well but large enough to permit a person to pass therethrough and to inspect the bottom of the well, means for making a tight closure between the lower end of the tubular member and the bottom of the well, and means coacting with the tubular member for discharging air adjacent to the lower end thereof to agitate the material around the tubular member. 15
